UNITED STATES PATENT OFFICE.

ARTHUR HINTZE, OF BERLIN-LICHTERFELDE, GERMANY.

APPARATUS FOR ASCERTAINING COLORS.

Application filed July 26, 1926, Serial No. 125,067, and in Germany July 29, 1925.

This invention relates to an apparatus for ascertaining colors, which is characterized by the fact, that upon each of the cards of celluloid, fan-like arranged around a common turning point, rectangular openings are disposed both in radial direction and in concentric rings, besides of which openings differently shaded off specimens of colors are fixed, which permit by glancing through them an immediate comparison with the observed object.

The reading of the specimen of color is given by the number of the fan-segment and secondly by the location of the color upon this fan-segment.

In the drawing the new apparatus is shown in a front view (Fig. 1) and in a side view (Fig. 2) of the closed apparatus and in a front view (Fig. 3) of the opened fan.

In the represented form of execution the apparatus contains five segmental cards of celluloid or of any other convenient material; these cards are designated by the numbers 1-5. Each of these cards contains a number of rectangular openings 6, on both sides of which are fixed specimens 6^a of colors, for instance upon the first card 1 yellow specimens shaded off till brown specimens; upon the second card 2 orange specimens shaded off till brown specimens and so on. This shading off of the colors takes place not only in the circumferential direction but in the radial direction of the rings *a*, *b*, *c* . . . , formed by the succeeding openings and specimens of colors. On the other hand the colors are shaded off from card to card.

The first card possesses a centrally located opening 7 which permits inspection of all the colors of the different cards; whereas each of the other cards shows an opening 8, 9, 10, 11, just beneath the opening 7 of the first card 1. This latter opening permits inspection of only the special colors of the cards 2, 3, 4 and 5. The numbers of the different cards are there repeated, for

instance 7₁, 8₂, etc., so that each can be quickly and easily found when desired.

The fulcrum point for the several cards 50 is formed in the known manner by a pin 12, passed through a central opening.

In the fan, constructed as above described, the gradations appertaining to one special color are found once by progressing along 55 a concentric zone, secondly by progressing in a radial direction and thirdly by pursuing the gradation of one special color from card to card; the gradations appear through the openings when small rotations take 60 place. This apparatus permits not only a close combination of numerous specimens in their relationship, but also the possibility of quickly finding the desired color of comparison, because all the colors, which are 65 approximately similar to the desired color are located immediately besides each other upon one fan-card and in a corresponding ring of one of the neighboring cards.

Besides these advantages, offered by the 70 new fan in comparison with prior forms of execution, as color steps for instance, the connection of all cards in one point around which they are rotatable, the facilities of manipulation are raised in a high degree. 75 Finally the readily flexible fan can readily be put on the objects.

The new model permits a hasty glance over approximately 200 colors, when 7-8 fan-cards are applied and each fan-card is 80 24 by 39 cm., and when the specimen of colors are 2,5 cm. high and not less than 1 cm. width. If the specimens have half the indicated dimensions and if they are doubly pasted, 400 colors can be looked over. 85

The new model is first of all thought for the "color standards" of Wilhelm Ostwald. But they can also be applied for the comparing determination of any other materials (woven materials, minerals, metals, glass) or 90 any other objects, as the case may be, when these objects are in a qualitative relationship with numerous similar materials or objects, and when this relationship is rep-

resented by a steady modification in three different directions.

Having now particularly described and ascertained the nature of my said invention and in what manner the same is to be performed, I declare that what I claim is:—

1. In a device for ascertaining colors, a plurality of cards of celluloid, means pivotally connecting the several cards together, each card having groups of openings arranged in rows concentric to the axes of the cards and spaced in the radial direction of

the said cards, differently colored specimens applied to the cards at the sides of said openings.

2. In a device as claimed in claim 1, characterized by the fact that the location of the specimen of color is given by the number of the fan segment and by the location of the color specimen thereon.

In testimony whereof I have signed my name to this specification.

DR. ARTHUR HINTZE.
